GOLF TEE HOLDER OR SIMILAR ARTICLE

Raymond R. Ward, North Royalton, Ohio

Application August 10, 1950, Serial No. 11,707

Term of patent 14 years

(Cl. D34—5)

To all whom it may concern:

Be it known that I, Raymond R. Ward, a citizen of the United States and a resident of North Royalton, in the county of Cuyahoga and State of Ohio, have invented a new, original, and ornamental Design for a Golf Tee Holder or Similar Article, of which the following is a specification, reference being had to the accompanying drawings, forming a part hereof.

In said drawing, Fig. 1 is a front perspective view of a golf tee holder or similar article showing my new design; Fig. 2 is a rear perspective view thereof; Fig. 3 is a vertical sectional view, on the line 3—3 of Fig. 4; and Fig. 4 is a cross sectional view, on the line 4—4 of Fig. 3.

I claim:

The ornamental design for a golf tee holder or similar article, as shown.

RAYMOND R. WARD.
